UNITED STATES PATENT OFFICE.

DANIEL A. KEATING, OF BRIDGEPORT, CONNECTICUT, ASSIGNOR TO THE AMERICAN TUBE AND STAMPING CO., OF BRIDGEPORT, CONNECTICUT, A CORPORATION OF CONNECTICUT.

VARIABLE-SPEED ROLLING MILL.

Application filed November 27, 1925. Serial No. 71,820.

The present invention relates to a variable speed drive for rolling mills, particularly for high speed Belgian train mills, an object being to provide driving means adapted, without the use of additional or substituted parts, to effect variable speed of the rolls with a constant motor drive. Heretofore it has been the custom to drive a series of meshing superimposed gears from the prime mover or motor drive, and connect these gears directly to the rolls, so that in order to vary the speed it was necessary to replace such gearing with gears of different size, with the consequent delay in the operation of the mill.

It is proposed, in the present embodiment of the invention, to provide change speed means by which the speed of the rolls may be quickly changed with facility, and without appreciable delay in the operation of the mill. A further object is to provide such means which may be readily incorporated in existing types of mills.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a front elevation of a rolling mill, according to the present embodiment of the invention;

Fig. 2 is a vertical sectional view, enlarged, of the change speed gears employed; and

Fig. 3 is a front elevation thereof, enlarged.

Similar reference characters indicate corresponding parts throughout the several figures of the drawings.

Referring to the drawings, the rolling mill, according to the present embodiment of the invention, comprises a base or foundation 10 provided with a longitudinal pit 11, at each side of which there are arranged parallel tracks 12 and 13, upon which the aligned gear and roll stands 14 are supported for longitudinal adjustment. These stands, as shown in Fig. 2, have base portions 15 adapted to slidably seat upon the tracks 12 and 13, and vertically grooved uprights in which the bearing chocks 16

are engaged for vertical disengaging movement, and are retained in fixed relation by a pressure screw 17 in the top of the stand. The upper chock 16^a is removable laterally upon disengagement of the retaining clips 18.

In a mill of this type a series of sets of rolls are arranged end to end in the stands and are coupled together, the illustration showing two such sets of rolls 19 and 20 comprising three rolls each, their projecting wabbler ends 21 being connected by means of spindles 22 and coupling bosses 23, so that the several sets of rolls are simultaneously rotated, one from the other.

In the usual practice a single set of gears is provided for the rolls, these gears being driven directly by the motor. According to the present invention two sets of gears are provided, the set adjacent the rolls 19 comprising three equal diameter superimposed gears 24, 25 and 26 of the herring bone type, having their wabbler ends 27 connected at one side by spindles 28 and couplings 29 to the wabbler ends of the respective rolls. The second set of gears comprises three gears 30, 31 and 32, the intermediate gear 31 being of greater diameter, while the gears 30 and 32 are of equal diameter, these gears adapted to be driven directly by the motor drive, and in turn to drive the roll driving gears 24, 25 and 26.

The motor 33 is mounted upon a stand 34 at one end of the base 10, its shaft 35 being connected by a coupling 36 to a spindle shaft 37 journaled in suitable bearing supports 38 and 39 in substantial axial alignment with the center gears and rolls, and provided at its inner end with a coupling head 40. This head 40 is connected by a spindle 41 and coupling 42 to the wabbler end 43 of the gear 31. A spindle 44 having couplings 45 and 46 at its ends is adapted to be interchangeably and selectively connected between the wabbler ends 47, 48 and 49 of the respective gears 30, 31 and 32 and the opposed wabbler ends 50, 51 and 52 of the gears 24, 25 and 26, and by such selective interchange to effect different driving speeds between the two gear sets, and therefore between the motor drive and the rolls.

Thus as illustrated the large gear 31 is driven directly from the motor, the smaller

gear 32 is driven at greater speed by the gear 31, and said gear 32 in turn drives the gears 24, 25 and 26 at such relatively greater speed. By coupling the spindle 44 between the wobbler ends 48 and 51 of the gears 31 and 25 a straight through drive is provided at the same speed as the motor drive. By reversing the positions of the gears 31 and 32, driving the small gear 32 directly from the motor drive and driving the roll driving gears through the large gear 31, said roll driving gears are driven at relatively slower speed than the motor drive. It will be understood that the upper gear 30 may if desired be of larger diameter than the gear 31, so that the relatively slower roll driving speed may be provided by coupling such larger gear 30 to the roll driving gears. As shown, however, it is of equal diameter to 20 the gear 32 and may be interchangeably operated therewith for the purpose of equally distributing wear.

I have illustrated and described a preferred and satisfactory embodiment of the invention, but it will be obvious that changes may be made therein, within the spirit and scope thereof, as defined in the appended claims.

Having thus described my invention, what 36 I claim and desire to secure by Letters Patent is:—

1. In a rolling mill drive, a plurality of superimposed rolls, gearing for driving said rolls, a plurality of different diameter meshing gears, a motor drive connected to said gears at one side, and means for connecting

to any one of said gears to said roll driving gearing.

2. In a rolling mill drive a plurality of superimposed rolls, a plurality of superimposed meshing gears connected to said respective rolls, a plurality of different diameter meshing gears, a motor drive connected to said gears at one side and a detachable coupling between one of said last mentioned gears and one of said first mentioned gears.

3. In a rolling mill drive a plurality of superimposed rolls, a plurality of superimposed meshing gears connected to said respective rolls, a plurality of different diameter meshing gears, a motor drive connected to one of said gears at one side, and a detachable coupling between one of said last mentioned gears and one of said first mentioned gears.

4. In a rolling mill drive, a plurality of rolls, gearing for driving said rolls, a plurality of different diameter meshing gears, a motor drive connected to said gears, and means for selectively connecting said gears to said roll driving gearing.

5. In a driving mechanism for a rolling mill, gearing for driving the rolls of the mill, a plurality of different diameter meshing gears, a motor drive connected to said gears, and means for connecting any one of said gears to said roll driving gearing.

Signed at Bridgeport in the county of Fairfield and State of Connecticut this 14th day of November A. D. 1925.

DANIEL A. KEATING.
